UNITED STATES PATENT OFFICE.

MESHACH HOPKINS, OF LONDON, ENGLAND, ASSIGNOR OF ONE-HALF TO
WILLIAM H. CORK, OF CHICAGO, ILLINOIS.

SPEED-GEAR.

SPECIFICATION forming part of Letters Patent No. 570,638, dated November 3, 1896.

Application filed September 16, 1895. Serial No. 562,670. (No model.) Patented in England June 13, 1893, No. 11,593.

To all whom it may concern:

Be it known that I, MESHACH HOPKINS, a subject of the Queen of England, residing at Peckham, London, county of Surrey, England, have invented certain new and useful Improvements in Speed-Gears, (for which I have obtained Letters Patent in Great Britain, No. 11,593, dated June 13, 1893,) of which the following is a specification.

10 This invention relates to a gear which, without stopping the machine to which it is attached, may be adjusted so that the speed transmitted therethrough may either equal or be increased within certain limits to any 15 desired extent beyond that imparted to it.

The invention is specially applicable to cycles, in which connection it is hereinafter described; but it may be applied to various other machines.

20 In the accompanying drawings, Figure 1 is a view, partly in section and partly in elevation, of as much of a cycle as is necessary to illustrate the application of my invention thereto. Fig. 2 is a section on line 2 2 of Fig.

25 1. Fig. 3 is an elevation of the right-hand side of the lower part of Fig. 1. Fig. 4 is a section on line 4 4 of Fig. 1, and Fig. 5 is a perspective view of part of the adjusting mechanism of the gear.

30 Like letters indicate like parts throughout the drawings.

In carrying my invention into practice I key or otherwise rigidly secure upon or form in part with the crank or driving axle A an 35 eccentric or eccentric-bearing B and a flange or arm C, which may either be circular in the form of a disk concentric with the axle or a segment of a disk. For convenience the flange C is hereinafter referred to as a disk, 40 in which form it is shown in the drawings. On the bearing B is mounted a ring or wheel D, formed with a peripheral groove D', and two notched or toothed flanges D², all hereinafter collectively referred to as the "chain-wheel" D. This chain-wheel is free to rotate 45 on the eccentric-bearing B, which, if desired, may be provided with balls or other antifriction devices, although such are not represented in the drawings.

50 The disk C is provided with a chain-carrier comprising two studs C', rigidly secured in the disk, two rollers E, mounted on and free

to rotate on the studs, and between the two rollers E a block E', pivoted to the disk C. The last-described device, which as a whole 55 is hereinafter referred to as the "chain-carrier" E, serves to support an endless chain F, which while rotated bodily along with the chain-carrier E around the axis of the axle A is also capable of rotating in the direction 60 of its length around the said chain-carrier.

The chain F works in the groove D' of the wheel D, and all or some of its joint-pins, for example, as shown in the drawings, every alternate joint-pin F', are extended laterally 65 of the chain, so as to engage with the notches of the flanges D², as shown in Figs. 1 and 2.

G is an internally-toothed wheel mounted concentrically to and capable of rotating independently of the axle A, and in the example illustrated is rigidly secured between two cups H H', forming the hollow boss of a wheel H², of which only the central part is shown in Fig. 1. The wheel G is formed with a groove G' and two notched or toothed flanges 70 G², all hereinafter collectively referred to as the "chain-wheel" G, and with this wheel the outer part of the chain F engages, the inner part of said chain engaging, as before explained, with the chain-wheel D. 75

On the axle A is rigidly secured a collar A', which forms a running-surface for a ring of balls I, on which is supported the inner end of a short hollow shaft or sleeve J, whose outer end is similarly supported on a ring of 85 balls I', free to rotate between a bearing-collar I², adjustable on the shaft A, and a cup J', secured on the sleeve J, as by screwing and a key or pinching-screw. The inner end of the sleeve J is cupped and hardened or provided with a separate hardened-steel cup J² at the part where it runs upon the balls I and at this end it also has rigid upon it a flange or disk J³, in which is formed a radial slot or recess J⁴, with which engages a pin D³, 90 secured to the chain-wheel D, these two parts—viz., the sleeve J and chain-wheel D—95 always rotating together and at the same speed.

The sleeve J is free to rotate in a ball-bearing K in the lower end of the fork-arm K', the corresponding fork-arm K² at the opposite side of the wheel H² being provided with a ball-bearing K³, in which the axle A is free to

rotate. The inner end of the cup J' , as shown in Fig. 1, may itself constitute a portion of the race within which the balls of bearing K run.

5 The hollow boss H H' at one side is supported directly by the axle through the medium of a ball-bearing H^3 , and at the other side by the sleeve J through a ball-bearing H^4 .

The before-mentioned cup J' is provided 10 with a notched or toothed flange or rim J^5 , with which are adapted to engage a detent or stop L , and also, if desired, the spring end L' of a plate or arm L^2 , on which the stop is carried. The spring end L' may, however, be 15 entirely dispensed with.

M is a lever pivoted at M' to the handle-bar N of the cycle and adapted to be operated by the hand of the rider. This lever is provided with a spring-controlled detent M^2 , 20 capable of engaging with the notches 1, 2, and 3 of a collar N' , secured on the handle-bar N . To the lever M is pivoted the upper end of a link O , whose lower end is pivoted to a lever-arm P , secured on one end of a short shaft 25 P' , pivoted in the fork-arm K' . On the opposite end of the shaft P' is secured an eccentric P^2 , Figs. 3, 4, and 5, in which is mounted a crank-pin P^3 , for a purpose hereinafter specified. The eccentric P^2 is located between the 30 arms of a fork or yoke Q , secured on one end of a short shaft Q' , pivoted in the fork-arm K' , and on the other end of the shaft Q' is secured an arm Q^2 , connected by a link Q^3 to a similar arm Q^4 , secured on the outer end of 35 a short shaft Q^5 , pivoted in a downward extension K^4 of the fork-arm K' . On the inner end of the shaft Q^5 is secured an arm Q^6 , carrying a brake block or shoe Q^7 , which, like a similar brake-shoe Q^8 , securely mounted on 40 the before-mentioned yoke Q , is adapted to bear upon the periphery of a brake-disk Q^9 , secured, as by a pinching-screw Q^{10} , upon the sleeve J .

In the disk Q^9 is formed a perforation 45 through which passes a pin or stud R , rigidly secured in a disk R' , formed in part with a sleeve R^2 , which is capable of sliding in the direction of its axis on the before-described sleeve J . The sleeve R^2 is provided with a 50 peripheral groove R^3 , with which engages, as shown in Fig. 4, a spring-plate S , secured at its lower part to the fork extension K^4 . The pin R in certain positions of adjustment, as hereinafter explained, is adapted to engage 55 with a clutch projection or abutment-surface H^5 in the adjacent part of the cup H' , while at other times it is withdrawn from and held out of engagement with the projection H^5 by means of a spring T , interposed between the 60 two disks Q^9 R' , the whole forming a spring-controlled clutch.

The upper end of the spring-plate S is bent 65 outward, so that it may be acted upon by cams T , carried by a yoke or frame T' , pivoted on the before-mentioned crank-pin P^3 . The arms of the frame T' are provided with lugs T^2 , which by bearing against the edges

of the spring-plate S prevent the frame from moving out of position while allowing it to move up and down under the influence of the 70 eccentric P^2 .

The operation of the before-described apparatus is as follows: The device is shown adjusted for obtaining the maximum speed of rotation of the wheel H^2 in relation to the 75 rotation of the axle A . When it is desired to travel at a slow speed, the lever M is raised to its highest position, so that the detent M^2 will engage with the notch 1. By this operation the lever-arm P is raised, and through the shaft P' and crank-pin P^3 the yoke T' is also raised, and through the cams T , spring-plate S , and sleeve R^2 the pin R is moved into the path of the projection H^5 , so that the hollow boss H H' , with the internal-toothed wheel G fixed thereto, and the sleeve J , with the toothed wheel D connected therewith, are thereby locked together. By this same operation also, through the eccentric P^2 and its accessories, the former being turned 80 in the direction indicated by the arrow p in Fig. 3, the brakes Q^7 Q^8 are moved out of contact with the disk Q^9 , as shown in chain lines in Fig. 3. When, therefore, under this condition of adjustment, the axle A is rotated, 85 the chain-carrier E is rotated along with it, as it always is, and the chain is also moved with it, but as by said adjustment the sleeve J , to which (through the slotted disk J^3 J^4 and pin D^3) the chain-wheel D is secured, and the hollow boss H H' , carrying the chain-wheel G , are locked together the chain cannot rotate in the direction of its length or independently of the chain-carrier, the result of which is that any rotation imparted to the axle A must 90 without variation in speed or direction be transmitted through the chain F to the chain-wheels D and G , all the last-named parts rotating as one piece.

When it is desired to travel at an accelerated speed, that is to say, that the wheel H^2 should rotate quicker than the axle A , the lever M is lowered so that the detent M^2 engages with the notch 2, which operation, through the crank-pin P^3 , lowers the cams T , and thereby 100 allows the spring T to withdraw the pin R from out of the path of the projection H^5 , thereby leaving the wheel H^2 free to rotate independently of the sleeve J , the brake-blocks Q^7 Q^8 by this same operation being caused to 105 bear with a medium amount of pressure upon the brake-disk Q^9 . By the raising of the link Q^3 the spring or spring end L' (when such is 110 provided) is brought into engagement with the notched flange J^5 , so that when the axle 115 is rotated said flange J^5 is also capable of rotating, but only under the retarding influence of the brake-blocks Q^7 Q^8 or brake-blocks and spring L' , the result being that as the chain 120 F is rotated bodily around the axis of rotation of the axle A it is also caused (by the resistance presented by Q^7 Q^8 or Q^7 , Q^8 , and L') to rotate in the direction of its length independently of the axle, and thus impart to the 125

wheel H^2 a higher speed of rotation than that of the axle A. When the lever M is moved from its last-mentioned position to the lowest position, (in which latter the device is represented in the drawings,) the detent M^2 engages with the notch 3, and the only other material difference is that the brake-blocks Q^7 Q^8 are caused to bear with their maximum power on the brake-disk Q^9 and the stud L is brought into engagement with the toothed flange J^5 , so as to positively prevent any rotation of the sleeve J, the result being that as the chain F is carried around with the axle A and the chain-wheel D locked said chain must rotate in the direction of its length independently of and to its maximum speed in relation to the rotation of the axle, the wheel H^2 consequently being rotated at its maximum speed, the ratio of the speed of the wheel H^2 and axle A depending upon the relative diameters of the wheels D and G.

As shown in Fig. 1, the chain-carrier is mounted upon the disk C in such a manner as to be diametrically opposite the eccentric bearing B, and as both the disk and the eccentric are rigid with the shaft they maintain this relative position always. Such a provision affords space between the chain-wheel D and the annular gear G for the carrier-block to move in as it carries the chain around the shaft, the chain itself keeping up an independent rotation under the action of the chain-wheel D. Thus it is possible to employ a larger chain-wheel by mounting it eccentrically rather than concentrically, and so to increase the ratio of the speed between the driven wheel and the driving-shaft. I would employ a chain instead of a spur-gear upon the revolving arm, even were the chain-wheel D concentrically mounted, since it is thus possible to obviate the difficulties which would otherwise arise from the use of too small an intermediate spur-gear with its necessarily small teeth and the consequent danger of breaking.

By means of the brake device Q^7 Q^8 Q^9 and, if it be provided, the spring L' the pressure necessary for retarding and stopping the rotation of the sleeve J is gradually applied, so that the change for obtaining an increase of speed may be made without too great a shock being imposed on the rider.

From the foregoing the manner of adjusting the gear for a reduction of speed will be sufficiently understood to render any special description thereof unnecessary.

If desired, other mechanism than that before described may be used for locking and releasing the wheel D or disk J^3 , and moreover the speed-gear may be applied to machines other than cycles and, if desired, in the reverse manner, that is to say, the wheel G may be driven first and the motion therefrom transmitted to the wheel D, so as to enable the speed to be decreased instead of in-

creased, as before described. The chain F and teeth of the wheels D and G may be of the ordinary type instead of the form shown.

The device may be applied to the driving-chain wheel of a rear-driving cycle instead of, as shown in the drawings, directly to the road-wheel.

I claim—

1. The combination with the driving and driven parts of a speed-gear, and an eccentric-bearing and chain-carrier, comprising an anti-friction-rollers on one part, a chain-wheel on the eccentric-bearing and a chain-wheel on the other part, and chain gearing with both chain-wheels, of a pin on the eccentrically-mounted chain-wheel, a slotted flange engaging the pin, a toothed flange rigid with the slotted flange, a detent for the toothed flange, a lever for operating the detent, and link mechanism in operative connection with the detent and lever substantially as set forth.

2. The combination with the driving and driven parts of a speed-gear and an eccentric-bearing and chain-carrier on one part, a chain-wheel on the eccentric-bearing, a chain-wheel and clutch projection on the other part, a chain gearing with both chain-wheels, a flange, a pin-and-slot connection between this flange and the eccentrically-mounted chain-wheel, and a disk rigid with the flange, of a clutch permanently engaged with the disk for engaging with the clutch projection, a clutch-lever and link-and-lever mechanism in operative connection with the clutch and clutch-lever, substantially as set forth.

3. The combination with the driving and driven parts of a speed-gear and an eccentric-bearing and chain-carrier on one part, a chain-wheel on the eccentric-bearing, a chain-wheel and clutch projection on the other part, a chain gearing with both chain-wheels, a flange, a pin-and-slot connection between this flange and the eccentrically-mounted chain-wheel, and a disk rigid with the flange, of a clutch permanently engaged with the disk for engaging with the clutch projection, a sleeve carrying the clutch, a cam for moving the sleeve, and a crank-pin, lever-arms, links and a clutch-lever all operatively connected together, substantially as set forth.

4. The combination with the driving and driven parts of a speed-gear and an eccentric-bearing and chain-carrier on one part, a chain-wheel on the eccentric-bearing, a chain-wheel and clutch projection on the other part, a chain gearing with both chain-wheels, a flange, a pin-and-slot connection between this flange and the eccentrically-mounted chain-wheel, and a disk rigid with the flange, brake-shoes adapted to bear on the disk, lever-arms carrying the brake-shoes, a clutch permanently engaged with the clutch projection, a sleeve carrying the clutch, a cam for moving the sleeve, a crank-pin for moving the cam, and a brake and clutch lever and lever-and-

link mechanism in operative connection with the brake and clutch devices, substantially as set forth.

5. The combination with the driving and driven parts of a speed-gear, of an eccentric-bearing and chain-carrier on one part, a chain-wheel on the eccentric-bearing, a chain-wheel and clutch projection on the other part, a chain gearing with both chain-wheels, a pin 10 on the eccentrically-mounted chain-wheel, a slotted flange engaging the pin, a toothed flange and a disk rigid with the slotted flange, a clutch permanently engaged with the disk, a detent to engage the toothed flange, brake- 15 shoes to bear on the disk, a cam to move the clutch into engagement with the clutch projection, an operating-lever and link-and-lever mechanism in operative connection with this lever and the detent, brake-shoes and cam, 20 substantially as set forth.

6. The combination with the driving and driven parts of a speed-gear, an eccentric-bearing and a chain-carrier upon one of said parts, a chain-wheel upon said eccentric-bearing, a chain-wheel concentric with the shaft, and a chain upon said carrier confined between and engaging said chain-wheels of a pin upon the eccentrically-mounted chain-wheel, a sleeve upon said shaft provided with 25 30 a slotted flange engaging said pin, a toothed flange rigid with said sleeve, a detent for the toothed flange, and link-and-lever mechanism in operative connection with the detent, substantially as set forth.

35 7. In a speed-gear, the combination of a shaft, an eccentric-bearing rigid therewith, a chain-wheel loosely mounted on the eccentric, a brake for the chain-wheel, an annular gear mounted concentrically with and capable of independent rotation upon said shaft, an arm rigid with the shaft, a chain-carrier attached thereto to rotate about said chain-wheel, and an endless chain upon the carrier confined between said annular gear and chain-wheel, free to revolve about the carrier under 40 45 the action of the chain-wheel when the shaft is turned and the chain-wheel retarded, substantially as and for the purpose set forth.

8. In a speed-gear, the combination of a 50 shaft, a chain-wheel loosely mounted thereon, a brake for said wheel, an annular gear mounted concentrically with and capable of

independent rotation upon said shaft, an arm rigid with the shaft, a chain-carrier attached to the arm between said chain-wheel and an- 55 nular gear, and an endless chain upon the carrier between the chain-wheel and annular gear, substantially as and for the purpose set forth.

9. In a speed-gear, the combination of a 60 shaft, a chain-wheel loosely mounted thereon, a brake for said wheel, an annular gear mounted concentrically with and capable of independent rotation upon said shaft, an arm rigid with the shaft, a chain-carrier attached 65 to the arm, an endless chain upon the carrier confined between said annular gear and chain-wheel and free to rotate about said chain-carrier under the action of the chain-wheel, and means for locking the parts together, sub- 70 substantially as and for the purpose set forth.

10. In a speed-gear, the combination with the driving and driven parts, of an eccentric-bearing and chain-carrier on one part, a chain-wheel on the eccentric-bearing, a chain-wheel 75 on the other part, and an endless chain upon said carrier confined to rotate between and geared to said chain-wheels as it is itself carried around one of said chain-wheels in the operation of the gear, substantially as de- 80 scribed.

11. In a speed-gear, the combination of a shaft an eccentric-bearing rigid therewith, a chain-wheel on said bearing, a chain-wheel mounted concentrically with and capable of 85 independent rotation upon said shaft, an arm rigid with the shaft, a chain-carrier upon the arm, a chain upon said carrier engaging the chain-wheels, a sleeve upon the shaft having a flange provided with a radial slot, a pin upon 90 said eccentrically-mounted chain-wheel engaging said slot, brake-shoes engaging said sleeve, lever-arms carrying the brake-shoes, a brake-lever and link-and-lever mechanism in operative connection with the lever-arms 95 and brake-lever, substantially as set forth.

In testimony whereof I have hereto set my hand in the presence of the two subscribing witnesses.

MESHACH HOPKINS.
